SHIPPING CONTAINER

Frank O. Wright, Memphis, Tenn.

Application March 8, 1943, Serial No. 478,389

1 Claim. (Cl. 217—72)

This invention relates to new and useful improvements in shipping containers and like receptacles, the principal object being to construct a container or receptacle of plywood and sufficiently strong and durable to permit the transportation therein of slack and other heavy materials.

Another important object of the invention is to provide a container structure divided into upper and lower sections which can be readily disconnected to the end that the sections can be stored by being inter-nested in a very limited space.

Other objects and advantages of the invention will become apparent to the reader of the following description.

In the drawing:

Figure 1 is a top plan view of a basket type of container.

Figure 2 is a section on the line 2—2 of Figure 1.

Figure 3 is an enlarged fragmentary detailed sectional view showing the top and retaining band about to be applied.

Referring to the drawing, wherein like numerals designate like parts, there is disclosed a basket-type container embodying one form of this inventive concept and comprising an inverted frusto-conical-shaped side wall 50 made up of plies 51, 52 and 53 suitably secured at the lower ends to a fixed bottom 54.

The upper edges of the plies 51, 52 and 53 are slit as at 55, these slits being staggered so that they do not horizontally register. The purpose of these slits is, of course, to permit flexation of the upper edge portion of the side wall 50.

The slits serve to define tongues 56, the tongues of the innermost ply 51 each having upper and lower cleats 57, 58.

Numerals 59 denotes a contracting band for the upper portion of the wall 50, while numeral 60 40 denotes a top for the basket type container.

It can now be seen, that normally the upper edge portion of the wall 51 flares in the manner shown in Figure 3 so that the top 60 can readily be placed in position between the upper and lower cleats 57, 58. The contracting band 59 can now be worked upwardly on the wall 50 so as to contract the upper edge portion of the wall 50 and bring the cleats 57, 58 into overlapping relation with the top and bottom sides of the top 60, thus firmly securing the top to the container.

While the foregoing specification sets forth the invention in specific terms, it is to be understood that numerous changes in the shape, size and materials may be resorted to without departing 10 from the spirit and scope of the invention as claimed hereinafter.

Having described the invention, what is claimed as new is:

In a barrel structure, a flaring wall being longitudinally slotted at one end to provide a multiplicity of finger extensions, each finger extension being provided with a pair of longitudinally spaced abutments thereon, a closure, the inner circumferential row of abutments defining a circle of a diameter less than that of the closure, the outer circumferential row of abutments defining a circle having a diameter greater than the diameter of the closure to permit placement of the peripheral portion of the closure against 20 the inner row of abutments preparatory to closing the barrel, and a slip ring of a diameter less than the circumference of the barrel at the finger extensions, said ring being adapted to be slid to a position contracting the finger extensions 25 toward the periphery of the closure to maintain the rows of abutments on opposite sides of the closure.

FRANK O. WRIGHT.
